UNITED STATES PATENT OFFICE

WILLARD WALTER, OF MONGO, INDIANA

TROUSER CREAMER

Application filed December 2, 1927. Serial No. 237,324.

My invention relates to trouser creamers and has as its object to provide an apparatus wherein no rivets, bolts, etc. are used for fastening the elements operatively together.

5 Another object is to provide a creamer that may be taken apart without tools, and folded for carrying in a traveling bag or placing in a drawer.

With these and other objects in view, my 10 invention resides in the novel construction and arrangement of parts as hereinafter described and claimed.

In the drawing

15 Figure 1 is a side view of my device shown as engaging a pair of trousers in use;

Figure 2 is a reverse side view of my device in use;

Figure 3 is an edge view of my device in use;

20 Figure 4 is an enlarged detail of a marginal portion of my device;

Figure 5 is an enlarged section along the line 5—5 in Figure 1;

25 Figure 6 is an enlarged section along the line 6—6 in Figure 2;

Figure 7 is an enlarged detail sectional view through a portion of the upper bearing plate of one of the creasing members showing one of the hooks for mounting the trans- 30 verse bars.

In carrying out my invention, I provide two sections A and B hereinafter referred to as the upper and lower sections respectively. Each section is formed of the oppositely 35 positioned longitudinal creasing members C and D releasably joined together at E. The said creasing members C and D are each formed of an upper leaf 1 and a lower leaf 2 hingedly connected at their margins, as

40 shown at 23. In the making of these leaves, elongated strips of suitable material are formed with the flat bearing plates 3 and are bent and formed at their margins upon longitudinal lines of flexure into the upstanding

45 double-ply flanges 4. Lips 5, integral with the said flanges 4, are bent around a hinge wire 6 so that the creasing members may be swung open to receive a pair of trousers. This development is clearly shown in Figure 50 6. The ends of the lower members 2 of sec-

tion A are extended at 7 and given a corrugated form as shown at 8 in Figure 6. The adjacent ends of the lower bearing plates 2 of section B have a strap or loop 9 cut and pressed outwardly and given a corrugated 55 shape for forming a socket 10 for the extended corrugated ends 7 of section A. To hold the said creasing members C and D in the proper fixed relation, I provide the two transverse bars 11, U-shaped in cross section. 60 From the points 12 outward on the said bars 11, a lip 13 is turned at right angles to one of the sides 14 of the bars. Suitable slots 15 are cut through the flanges 4, adjacent the upper 65 and lower ends of the members C and D and are adapted to engage the lips 13 of the channel bars 11 so that the sections C and D may be held in through proper position in a common plane. I line the inside surfaces of the bearing plates 3 with a suitable cloth 16 upon which the trousers rest while in the process of creasing. To hold the upper and lower leaves 1 and 2 tightly against the trousers, I provide the transverse U-shaped 70 channel bars 17 substantially the same as the bars 11. Hooks 18 are pivoted through a small raised portion 19 of the upper bearing plates 3 upon the creasing members D. These said hooks 18 have the angularly extended prongs 20 so that the bars 17 may be 75 slipped in them in a lateral direction and secured from slipping either upward or downward. Open hooks 21 are pivoted in the raised portions 22 of the upper bearing plates 3 of the creasing members C, being 80 positioned in transverse alignment with the said hooks 18. The hooks 21 being open, the ends of the said transverse bars 17 may be 85 brought into engagement therewith in a swiveling movement upon the hooks 18. 90

From the foregoing description, it may be easily understood that the creasing members may be held in the proper spaced relation while the trousers are placed therein and great pressure be brought to bear by placing 95 the transverse bars in the hooks.

While I have herein set forth a preferred embodiment of my invention, it is understood that I may vary from the same in minor details, not departing from the spirit of my 100

invention as defined in the appended claims.

I claim:

1. In a device of the kind described, a pair of oppositely positioned creasing members, each such member comprising two leaves of strip sheet metal hingedly connected at their outer margins, the said leaves having perpendicularly turned flanges along their edges, the two corresponding leaves of each pair having the said flanges slotted near their ends, and two U-shaped bars formed of strip sheet metal, the said bars having lips turned perpendicularly from one side near the ends of the bars, for transversely engaging the said slotted ends of the said two leaves, for holding the said leaves fixed in a common plane.

2. In a device of the kind described, a pair of oppositely positioned creasing members, each such member comprising two leaves of strip sheet metal hingedly connected at their outer margins, the said leaves having perpendicularly turned flanges along their edges, the two corresponding leaves of each pair having the said flanges slotted near their ends, and two U-shaped bars formed of strip sheet metal, the said bars having lips turned perpendicularly from one side near the ends of the bars, for transversely engaging the said slotted ends of the said two leaves, for holding the said leaves fixed in a common plane, hooks upon the outer faces of the other two leaves, and bars adapted to transversely engage said hooks for holding those leaves pressed upon their hingedly connected companion leaves.

In testimony whereof I affix my signature.
WILLARD WALTER.
